[57] CLAIM

The ornamental design for a vehicle seat or similar article, as shown and described.

DESCRIPTION

FIG. 1 is a front perspective view of a vehicle seat or similar article which illustrates the new design;

FIG. 2 is a front elevation view thereof;

FIG. 3 is a side elevation view thereof;

FIG. 4 is a top plan view thereof;

FIG. 5 is a front perspective view of an alternative embodiment of a seat embodying the new design and which is identical to the seat illustrated in FIGS. 1-4, except that the left hand arm component is omitted. The rear of the seat is substantially plain and unornamented.

FIGS. 2, 3, and 4 have been drawn to a larger scale with respect to FIGS. 1 and 5.

FIG. 1.FIG. 2.FIG. 3.

FIG. 4.

FIG. 5.
